HAIR WAVER

Filed June 27, 1927

Inventor:

Josephine E. Schurger

UNITED STATES PATENT OFFICE.

JOSEPHINE E. SCHURGER, OF TWIN FALLS, IDAHO.

HAIR WAVER.

Application filed June 27, 1927. Serial No. 201,705.

- This invention relates to hair wavers, and is primarily intended for water waving of the hair, although the invention is susceptible of use in other connections.
- 5 The object thereof is for the better securing the combs and the hair in a fixed position, without the use of hair nets or the like.
- A further object is the making of a better wave.
- 10 A still further object is the simplicity in construction and its application.
- In the use of combs for water waving of the hair, it is customary to provide a pair of curved combs, the hair is moistened, and the 15 combs are then inserted in the hair with their teeth adjoining, the hair is raised or arranged between the combs as desired, and when the required number of such waves have been made, a hair net or the like is 20 firmly applied to keep the combs and hair in position until the hair becomes dry.
- In many instances it is hard to keep the combs and hair in proper position when moving about, especially if the occupant's 25 hair is not heavy or of a fine texture.
- My invention consists of a pair of combs made to conform to a bar and pivotally connected or hinged to one end of same, said bar preferably curved to the contour of the head, 30 having pockets or openings in the sides for receiving the teeth of said combs, the base or lower portion of the sides below the pockets is preferably of greater width than the portion above, said projection to extend around 35 both ends of the bar, for the purpose of hinging or pivotally connecting and supporting the ends of the combs, the outer sides of the projection or base extending along the sides are slightly inclined, for the 40 purpose of guiding the teeth of the combs to the pockets, and the projection is for supporting the ribs or backs of the combs when in closed and operative position. In its application after the hair has been moistened 45 the bar is inserted under the hair to be waved, keeping the hair in a raised position, the combs are then closed or brought together, the teeth passing through the hair into the pockets of the bar, the resilient 50 means on the end of one comb is placed over the projection on the end of the other, keeping them in closed and operative position.
- In the drawing wherein is illustrated a perspective view of my invention, 1 indicates the upper side of a preferably curved bar 55 made smooth and slightly oval with all of the edges rounded for preventing the cutting and breaking of the hair, 2 is the pocket or opening in the sides of the bar for receiving the teeth of the combs 6 and 7, 3 is the 60 base of the bar preferably extending outward and downward beyond the upper side face, for the purpose of acting as a guide for the teeth of the combs and a support for the rib or back of the combs when closed in 65 operative position, 4 is the end of the bar with support and pivotal attachment with ends 8 of each of the combs, 5 is the end of bar opposite from pivotal or hinged end and made to support the ends of the combs, 6 is 70 one of the combs made to conform with the side opening 2 in the bar, 7 is comb opposite from 6 and made to conform with opening 2 in the bar, 8 are the ends of the combs with provisions for hinging or pivotal attaching 75 with the bar at 4, 9 is end of comb 6 preferably with flexible means for attaching with end of comb 7, 10 is end of comb 7 having a projection for attaching with flexible means 80 9 of comb 6 when in closed and operative 85 position.
- It is to be understood that the bar can be made straight or curved to fit the contour of the head, and the combs are to conform to the pockets and the bar, and to be made of any suitable metal or material and any size.
- Having thus described my invention, what I claim is:
1. A hair waver comprising a bar and a pair of combs, said bar having pockets or 90 side openings for receiving the teeth of said combs, said bar having a projection around its base for a guide and support for said combs, one end of said combs being hinged or pivoted to one end of said bar with the 95 opposite ends of said combs having means for securing them in closed and operative position with said bar.
2. A hair waver comprising a curved bar and a pair of combs conforming with same, 100 said bar having pockets or side openings for receiving the teeth of said combs, said bar having a projection around its base for a guide and support for said combs, one end of said combs being hinged or pivoted to one 105 end of said bar, with the opposite ends of

said combs having means for securing them in closed and operative position with said bar.

3. A hair waver comprising a bar shaped to conform to the general outlines of the human head and provided with slots opening inwardly from opposite edges of the bar, a plurality of combs, each having its teeth

directed towards said bar, means pivotally mounting each comb for swinging movement 10 to bring its teeth into or out of one of said slots and means for retaining each comb in fixed relation to the bar with its teeth in the respective slot.

In testimony whereof I affix my signature,
JOSEPHINE E. SCHURGER.
